ATTORNEY

UNITED STATES PATENT OFFICE.

FREDERICK E. AHLERING, OF PORT READING, NEW JERSEY.

FOUNTAIN SHAVING-BRUSH.

1,252,380.

Specification of Letters Patent.

Patented Jan. 8, 1918.

Application filed September 17, 1915. Serial No. 51,260.

To all whom it may concern:

Be it known that I, FREDERICK E. AHLERING, a citizen of the United States, residing at Port Reading, in the county of Middlesex 5 and State of New Jersey, have invented certain new and useful Improvements in Fountain Shaving-Brushes, of which the following is a specification.

This invention has relation to certain new 10 and useful improvements in fountain shaving brushes, and has for its primary object, the provision of a shaving brush which will be of simple and compact form, and to the bristles of which may be readily fed a mixture of water and liquid soap.

The invention has for another object, the provision of a fountain shaving brush of this character which will be of such construction and operation that the flow of water and 20 liquid soap to the bristles may be readily controlled by the party using the brush.

The invention has for a further object, the provision of a fountain shaving brush of this character which will be composed of the 25 minimum number of parts of simple construction and which may be readily and cheaply manufactured.

With the above and other objects in view, the invention resides in the novel construction, combination, and arrangement of parts 30 as hereinafter set forth in the specification, pointed out in the claims, and shown in the drawings, in which—

Figure 1 is a longitudinal section through 35 the complete device with the movable feed valve in its outermost or receiving position;

Fig. 2 is a transverse section, substantially on the plane of line 2—2 of Fig. 1;

Fig. 3 is an elevation of the complete 40 device with the movable feed valve in its outermost or receiving position.

Referring more particularly to the drawings in which similar reference characters 45 designate corresponding parts throughout the several views, 1 designates the hollow body of the brush which is divided into longitudinally extending water and soap containing compartments 2 by means of a longitudinal transverse partition 3.

The hollow body 1 is provided with a removable cap 4 for its outer end to close the water and liquid soap containing compartments 2. At the opposite end of the hollow body 1 I provide a mixing chamber 5 formed 55 by the inner transverse partition 6 and outer transverse partition 7. The inner transverse

partition 6 serves as the end wall for the water and liquid soap containing compartments 2 and has suitable perforations 8 through which soap from said compartments 60 2 may pass into the mixing chamber 5 when the movable feed valve 9 is in its outermost or receiving position with the upper plate 10 thereof spaced from the perforations 8, while the lower plate 11 of said movable 65 feed valve 9 is positioned against the perforations 12 in the outer transverse partition 7, which also serves as the inner wall of the pocket 13 for the inner ends of the brush bristles 14. The connecting portion or neck 70 of the movable feed valve 9 is engaged against the outer wall of the hollow body 1 and has a guide pin 15 projecting through a guide slot 16 in said wall of the hollow body 1, by means of which the feed valve 9 may 75 be readily moved to its innermost or outermost position and will be properly guided. It will also be understood that the inner ends of the upper plate 10 and lower plate 11 are spaced from the side wall of the mixing 80 chamber 5 to permit the water and liquid soap from the compartments 2 to pass into and mix within said feed valve 9 while the same is held in its outermost position and then permit the mixed water and liquid 85 soap to pass out of the feed valve 9 and through the perforations 12 to the brush bristles 14 when said feed valve 9 is moved to its innermost position against the perforations 8.

While the preferred embodiments of the invention have been shown and described, it will be understood that minor changes in the details of construction, and arrangement of parts may be resorted to within the scope of 95 the appended claims without departing from the spirit of the invention or sacrificing any of the advantages of the same.

What is claimed is:

1. A shaving brush of the character described comprising a hollow body having a mixing chamber at one end and a removable cap at its opposite end, said body being divided into longitudinal compartments, said compartments being separated from the mixing chamber by the inner perforate wall of the latter, said mixing chamber having its outer wall perforated, bristles secured against said outer wall, and a movable feed valve within said mixing chamber and adapted for engagement respectively with the inner and outer walls of the same.

2. A brush of the character described comprising a hollow body having a mixing chamber, compartments communicating separately with said mixing chamber, bristles secured against one wall of said mixing chamber, said wall of the mixing chamber being perforated, and a suitable feed valve within said mixing chamber and spaced from one wall of the same, said feed valve being adapted for movement against the opposite walls of said mixing chamber.

3. A shaving brush of the character described comprising a hollow body having a mixing chamber and independent compartments communicating with said mixing chamber, bristles engaged against one wall of said mixing chamber, said wall being perforated, and a valve movable in said mixing chamber to control the passage of the contents of said independent compartments to said mixing chamber and the passage of the mixed contents of the mixing chamber to said bristles.

4. A shaving brush of the character described comprising a hollow body having a mixing chamber at one end formed by two spaced transverse partitions having perforations therethrough, independent compartments in the remainder of the body formed by a longitudinal partition and communicating with said mixing chamber, a brush fixed against the outer partition of said mixing chamber, and a valve in said mixing

chamber formed of two spaced parallel plates connected together at one side and movable in unison between the transverse partitions to control the passage of the contents of the independent compartments through the perforations in the inner partition into said mixing chamber, and the passage of the mixed contents of the mixing chamber through the outer perforated partition to said brush, said valve plates being spaced at one side from the wall of the chamber to permit the mixed fluids to enter the space between the plates when the valve closes the perforations in the outer partition and leave said space when the valve is moved into contact with the inner partition.

5. A shaving brush of the character described comprising a body having compartments formed therein, bristles secured in one end of said body, said bristles being separated from said compartments by a mixing chamber, and a manually movable valve within said mixing chamber having means to control the flow of liquids from the compartments to the mixing chamber and from the latter to the bristles.

In testimony whereof I affix my signature in presence of two witnesses.

FREDERICK E. AHLERING.
